DRESS FORM WITH RETRACTABLE SHOULDERS
Ann Baldwin, 334 E. 53rd St., New York, N.Y. 10022
Filed June 14, 1965, Ser. No. 463,700
2 Claims. (Cl. 223-68)

This invention relates generally to dress forms, and is especially concerned with unique improvements in dress forms for domestic use by the home sewer.

As is well known to those versed in the art, better-quality dress forms are relatively expensive and often beyond the financial reach of the average housewife or woman desirous and capable of making her own garments. While certain economical models for home use have been proposed, these suffer certain disadvantages, for example in being fabricated of inherently stiff material, such as cardboard or the like, seriously limiting the available contours, curves and shapes of the dress form. Another drawback of prior dress forms, also inherent in the stiffness or rigidity of material employed, was the need for opening seams to remove a dress from the form.

Accordingly, it is an important object of the present invention to provide a dress-form construction which overcomes the above-mentioned difficulties, is capable of fabrication from flexible sheet material to more accurately reproduce natural body contours, while affording the necessary rigidity for sustaining both itself and a garment under all conditions of use.

It is still another object of the present invention to provide a dress-form construction of the type described having a unique shoulder structure capable of inward depression when desired for removal and replacement of a garment with respect to the form, and return of the depressed structure, when desired.

It is still a further object of the present invention to provide a dress form having the advantageous characteristics mentioned in the preceding paragraphs, which is extremely simple to make, being capable of production at home by the ultimate purchaser with simple instructions, which is durable and reliable throughout a long useful life, and which can be economically manufactured in kit form for distribution and sale at a reasonable price.

Other objects of the present invention will become apparent upon reading the following specification and referring to the accompanying drawings, which form a material part of this disclosure.

The invention accordingly consists in the features of construction, combinations of elements, and arrangements of parts, which will be exemplified in the construction hereinafter described, and of which the scope will be indicated by the appended claims.

In the drawings:

FIGURE 1 is a front perspective view showing a dress form constructed in accordance with the teachings of the present invention, and in its normal condition of use.

FIGURE 2 is an enlarged, partial front perspective view showing a shoulder of the dress form of FIGURE 1, but in a compressed condition for removal from or placement on the form of a garment.

FIGURE 3 is a partial sectional view taken generally along the line 3-3 of FIGURE 1, and illustrating in dot-and-dash outline the depressed condition of FIGURE 2.

FIGURE 4 is a partial sectional elevational view taken generally along the line 4-4 of FIGURE 1.

FIGURE 5 is a partial sectional elevational view similar to FIGURE 4, but taken generally along the line 5-5 of FIGURE 2 and illustrating the depressed shoulder condition.

FIGURE 6 is a bottom perspective view of the lower body region.

2

FIGURE 7 illustrates a plurality of blanks adapted to be formed into the shoulder construction of the instant invention.

FIGURE 8 is an interior elevational view of the dress-form shoulder fabricated from the blanks of FIGURE 7.

FIGURE 9 is an interior elevational view similar to FIGURE 8 but illustrating adhesive tapes as reinforcing.

Referring now more particularly to the drawings, and specifically to FIGURE 1 thereof, a dress form is there generally designated 10, and is constituted of a hollow body 11 of generally torso-shaped configuration. The hollow body 11 includes a lower region or skirt 12, an intermediate region or waist 13, and an upper region or bust 14. The upper region or bust 14 is shaped to define a pair of shoulders 15 extending laterally outward away from each other and respectively terminating at sides 16, each formed with a side opening or armhole 17.

The body 11 may be pieced or otherwise formed in any suitable manner of flexible sheet material, such as felt, advantageously impregnated with sizing. While felt has been found satisfactorily for the outer layer of body 11, it is appreciated that plastic, or other suitable material may be employed, if desired. In conjunction with a felt outer layer, it has been found preferable to adhesively secure suitable stiffener means to the interior surfaces of the felt body material where stiffening is desired. Conforming engagement of the inner stiffening sheet material may be obtained by employing gum paper, or other adhesive-coated flexible sheet material in pieces formed with slits and cuts for conforming engagement with the various interior contours of the felt.

Interiorly of each shoulder 15 is provided stiffener means 20 of the type described. That is, the stiffener means 20 may be gum or adhesive-coated paper secured in facing engagement with the interior surface of the shoulder. Such stiffener means is shown in FIGURES 3-5, it there being illustrated that the stiffener means or adhesively secured paper 20 terminates at an edge 21 adjacent to but spaced from the body side 16 having the armhole opening 17. Thus, there is a terminal portion 22 of each shoulder 15 remaining unstiffened, and, therefore, relatively flexible as compared to the remainder of shoulder.

Each side or armhole opening 17 is closed by a generally circular closure piece 25, say of sized felt or other suitably flexible material and peripherally secured to the bounding margin of the respective opening, as by stitching 26 (FIGS. 3 and 7).

A closure piece 25 is shown in blank form in FIGURE 7. Also shown in blank are a pair of armhole-defining pieces 27 adapted to be secured together along their upper margins 28, there forming the extreme shoulder portion 22. The arcuately concave edge margins 29 of blanks 27 combine to define a side or armhole opening, while the vertical edge margins 30 are stitched or otherwise secured together to form body sides 16.

An additional pair of substantially identical blanks 31, being of opposite hand, are vertically elongate, including lower adjacent side edge margins 32 which are stitched or otherwise secured together, and upper inner side margins 33 of arcuately concave configuration for peripheral securing about respective halves of the closure piece 25. When the blanks 31 are thus secured to each other and to the closure piece 25, they combine to define a peripheral lip 35 (FIG. 8) extending circumferentially about the closure piece 25 interiorly of the body 11 adjacent to the relatively flexible shoulder portion 22. By the vertical elongation of the blanks 31, the lower region of lip 35 is extended to depend and provide a tongue 36. As best seen in FIGURE 8, the peripheral lip 35 is secured interiorly about the closure piece 25 as by a cir-

cumferential line of stitching 37, and the lower adjacent edges 32 of the blanks 31 are secured together by stitching 38. The lip 35 and its depending extension or tongue 36 is thus mounted interiorly of the body 11, being free from the body except as secured thereto peripherally about the closure piece 25 and at any one line of holes 31a.

In addition, a pull tab or loop 40 may be stitched or otherwise secured to each closure piece 25, as between the peripheral margin of the latter and the adjacent edge margin of arm opening 17, see FIGURES 4 and 5.

In addition to the stiffener means 20 adhesively secured to the interior surfaces of shoulders 15, there is stiffener means 42 secured to the interior surface of each closure piece 25 to stiffen the latter. The stiffener means 42 may also be of gummed paper, or other sheet material suitable for adhesive securing to the closure pieces. Further, the stiffener means 42 of each closure piece 25 may extend therebeyond for stiffening securing with the inner surface of the respective peripheral lip 35, as at 43, and with the inner surface of the respective depending extension or tongue 36, as at 44. Thus, each closure piece 25 and its associated lip 35 and tongue 36 are effectively stiffened as a unit, while remaining free or unsecured with respect to the body 11, except about the periphery of each closure piece. If desired, the lower ends of tongues 36 may be secured to the facing portion of side 16, without adversely affecting operation, as will appear presently.

As best seen in FIGURES 3 and 4, while the terminal portion 22 of each shoulder 15 remains unstiffened, and, therefore, relatively flexible, the underlying peripheral lip 35 is effectively stiffened or rigidified to support or reinforce the relatively flexible shoulder portion, and thereby permit use of the dress form 10 in the same manner as a conventional dress form having rigid shoulder terminal shoulders. However, by reason of the relatively flexible shoulder terminal portions 22, the closure pieces 25 are each depressible inward, as from the normal position of FIGURE 4 to the inwardly depressed position of FIGURE 5 (and the phantom position of FIGURE 3), the shoulder portion 22 flexing for this purpose. In such depressed condition, as seen in FIGURE 2, the overall width of dress form 10, at its shoulder region, is substantially reduced. This permits upward removal of a garment from the form 10 without previously necessary opening of seams. Of course, mere pulling of the tab 40 effects return of the depressed closure piece 25 to its normal outward position, where it remains until deliberately depressed again.

While felt and paper have been described hereinbefore as preferred materials, it is appreciated that other materials may be employed, if desired. Also, the internal stiffening may assume other constructions, although that of multiple pieces of slit or cut gummed paper has been found highly advantageous for accommodating to all desired dress-form contours.

The use of multiple pieces of gummed paper or adhesive tape is shown in FIGURE 6, the multiple pieces 18 being adhesively secured in facing engagement with the inner surfaces of the lower body region 12 to effectively stiffen the outer material of the body region. Also in FIGURE 9 is shown the employment of multiple pieces of gummed paper or adhesive tape interiorly of the torso and shoulder. In particular, larger adhesive pieces 19 may be secured in facing engagement with the interior surfaces of the upper body region, while a plurality of relatively small adhesive pieces 23 may be secured in con-

forming facing engagement with the interior of the bust 14. A multitude of intermediate-size adhesive pieces may be secured in facing engagement with the inner surface of the armhole closure, as at 24, and to the blanks 31 surrounding the armhole closure, as at 34. If desired, the relatively flexible shoulder portion 22 may be reinforced with internal adhesively secured pieces or strips, but not sufficient in number of stiffness to adversely affect the desired flexibility. That is, the shoulder portions 22 may be reinforced, but must remain relatively flexible, as compared to the adjacent regions. The area 22a between the line of circles 27a and the line of x's 27b, as seen in FIGURE 7 should be free of reinforcements.

Further, if desired, the lower or depending ends of tongues 36 may be flexibly secured to the adjacent waist portion 13 of the body 11, as by adhesive pieces or tape 39 extending across the tongues and secured to the interior of the body.

From the foregoing, it is seen that the present invention provides a dress-form construction which fully accomplishes its intended objects and is well adapted to meet practical conditions of manufacture and use.

Although the present invention has been described in some detail by way of illustration and example for purposes of clarity of understanding, it is understood that certain changes and modifications may be made within the spirit of the invention and scope of the appended claims.

What is claimed is:

- 30 1. A dress form fabricated of flexible sheet material and comprising a hollow torso-shaped body, said body including shoulders extending outwardly from each other and terminating in armhole openings, a closure piece secured across each of said openings, and stiffener means secured interiorly of said shoulders adjacent to and spaced from said closure pieces to afford relatively greater flexibility to the shoulder portions adjacent to said closure pieces, said closure pieces being depressible inward upon flexure of said adjacent shoulder portions for reducing the width of said body across the shoulders, an internal lip secured along the periphery of each closure piece closely underlying and unsecured to the adjacent relatively flexible shoulder portion, for reinforcing said shoulder portions without impairing flexibility thereof, said lips each extending circumferentially about the respective closure piece, and an extension on each lip depending interiorly along the adjacent body side for reinforcing said body sides without impairing flexibility thereof, the bottom end of said extension being secured to said body, the remainder of said lip being otherwise free from the adjacent body side.
- 45 2. A dress form according to claim 1, in combination with additional stiffener means secured interiorly to each of said closure pieces, the associated lip and lip extension for movement thereof as a unit upon depression of said closure pieces.
